UNITED STATES PATENT OFFICE.

EDWARD DANBERRY, OF CLE ELUM, WASHINGTON.

SAFETY ATTACHMENT FOR ELEVATORS.

1,174,126.

Specification of Letters Patent.

Patented Mar. 7, 1916.

Application filed May 9, 1914. Serial No. 837,517.

To all whom it may concern:

Be it known that I, EDWARD DANBERRY, a citizen of the United States, residing at Cle Elum, in the county of Kittitas and State of Washington, have invented a new and useful Safety Attachment for Elevators, of which the following is a specification.

This invention relates to safety attachments for elevators and is more particularly designed as an improvement upon the structure disclosed in Patent No. 1,015,726, issued to me on January 23, 1912.

One of the objects of the invention is to combine with an elevator, a means for gripping both the inner side and the front and back of each guide rail so that the guide rail is thus prevented from pushing outwardly away from the descending car and a more positive grip upon the rail is effected than would otherwise be possible.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is a view partly in section and partly in front elevation of a portion of an elevator having the present improvements combined therewith. Fig. 2 is a section on line A—B Fig. 1. Fig. 3 is a section on line C—D Fig. 1, the parts being shown in the positions assumed thereby while the attachment is gripping the guide rail. Fig. 4 is a section on line E—F Fig. 1.

Referring to the figures by characters of reference, 1 designates the guide rails and 2 designates a portion of the frame of the car of the elevator, said frame including the top beams 3 on which is mounted a tubular standard 4 having opposed longitudinal slots 5. A supporting cable 6 extends downwardly into the standard 4 and is provided at its lower end with an eye 7 to which are secured downwardly diverging chains 8 connected to the upper corners of the frame 2. These chains extend loosely through the

slots 5 and a coiled spring 9 is housed in the standard and bears downwardly upon the upper ends of the chains and upwardly against an interior shoulder 10 formed or secured in the standard 4. Under normal conditions, when the chains 8 and cable 6 are taut while supporting the car, spring 9 is held under compression.

A collar 11 extends around the upper end of the standards 4 and slidably mounted on the standard is a weight 12 connected by chains 13 to the cable 6. A spring 14 extends around the upper portion of the standard and bears at one end against the weight and at its other end against the collar 11. This spring is normally under compression, as will be seen by referring to Fig. 1.

A sleeve 15 is slidably mounted on the standard and has slots 16 through which the chains 8 extend loosely. This sleeve has lugs 17 extending into the slots 5 to hold the sleeve against rotation on the standard. Arms 18 are pivotally connected to the sleeve 15 at diametrically opposed points and diverge downwardly, these arms being slidably mounted in slots 19 in the sides of frame 2 and being normally supported at their free ends close to but out of contact with the inner sides of the respective guide rails 1. Springs 20 connect the top of the frame 2 to the sleeve 15 and are normally held under stress.

The parts thus far described, with the exception of the spring 14, have been disclosed in my patent hereinbefore mentioned.

Should the cable 6 break, thus relieving the car of its supporting means, the spring 14, being released, will expand and push the weight 12 downwardly along the standard 4 so that it will strike the sleeve 15 with considerable force. Spring 9 will at the same time expand, thus pushing the chains 8 downwardly so that they will become slack and will not retard the downward movement of the sleeve 15. This sleeve 15 will also be pulled downwardly by the springs 20 and during the movement of the sleeve 15 the arms 18 will be spread apart at their lower ends and forced into engagement with the inner sides of the guide rails 1. The operation of the arms 18 as herein described while effective, has been found to be faulty for the reason that it tends to spread apart the guide rails 1. In order to avoid this spreading action and at the same time add

materially to the effectiveness of the attachment, a shaft 21 is journaled along the outer side of each top beam 3, each shaft having an outwardly extending arm 22. Rods 23 are pivotally connected to the outer ends of these arms 22 and extend upwardly, their upper ends being pivotally connected to the sleeve 15, as shown at 24. Each shaft 21 has arms 25 depending therefrom and fixedly connected thereto, the arms on each shaft being disposed directly opposite the corresponding arms on the other shaft. The corresponding arms on the two shafts are connected by coiled springs 26 which are constantly under stress. Secured to the ends of each shaft 21 are cams 27 having toothed peripheries, the toothed portions of the cams being beveled so that, when the said cams are brought into engagement with the guide rails 1, they will not only serve to pinch the guide rails between them but also to draw the guide rails inwardly toward each other to a slight extent.

It will be apparent that as long as the sleeve 15 is supported in its elevated position while the car is being upheld by the cable 6, the rods 23 will pull on the arms 22 and thus hold the cams 27 out of engagement with the guide rails 1. When, however, the cable 6 breaks, thus causing the sleeve 15 to move downwardly as hereinbefore described, the springs 26 will pull inwardly on the arms 25, thus rotating the shaft 21 and causing the toothed peripheries of the cams to engage the front and back faces of the guide rails 1. Consequently the guide rails will be pinched between the cams and the gripping action exerted by the cams will increase in proportion to the

downward movement of the car so that positive stopping of the car is insured.

What is claimed is:—

The combination with a car, a tubular standard thereon, a supporting cable extending into the standard, and connections between the cable and the car, of a member slidably mounted on the standard, a spring for drawing said member toward the car, the connections between the cable and car constituting means for supporting the member against the action of its spring, a spring within the standard and engaging the supporting cable for shifting said cable longitudinally within the standard when the cable is parted, a weight slidably mounted on the standard, a spring bearing on the weight, a connection between the weight and supporting cable for holding the last named spring normally under compression, said spring constituting means for propelling the weight downwardly along the standard when the cable is parted, opposed shafts mounted for rotation upon the car, gripping members carried by and movable with the shafts, connections between the shafts and the slideable member whereby the gripping members are held normally inactive, and yielding means for automatically rotating the shafts to shift the gripping members to active positions during the movement of the slideable member out of its normal position.

In testimony that I claim the foregoing as my own, I have hereto affixed my signature in the presence of two witnesses.

EDWARD DANBERRY.
